UNITED STATES PATENT OFFICE

PAUL R. DELLING, OF HADDON HEIGHTS, NEW JERSEY

MEANS FOR STEAM GENERATION

Application filed December 12, 1930. Serial No. 501,792.

My invention relates to steam generation and comprises improved means for applying heat derived from vaporized fuel to the generation of steam. The invention is especially adapted for steam engine driven vehicles in which space and weight limitations are controlling factors.

The invention comprises a steam generator associated with a combustion chamber, a mixing chamber for receiving and mixing vaporized liquid fuel and air, and a vertically arranged grate forming the dividing wall or partition between the mixing chamber and the combustion chamber, said grate having a multitude of burner vents corresponding in area of distribution approximately with the cross-section areas of both chambers.

Means are provided whereby the combustible mixture formed in the mixing chamber, passes through the grate orifices or burner vents, to be burned in the combustion chamber, and the heat from the burning fuel is caused to move in substantially horizontal lines of travel through the steam generator or boiler. This horizontal movement of the heat of the flame and burnt products is secured by directing the combustible mixture through horizontally directed vents in the vertical grate by providing a tubular boiler arranged to facilitate the flow of heat therethrough uniformly distributed and in substantially horizontal lines of travel, and by discharging or withdrawing the burnt products from near the bottom or lower part of the space provided on the side of the boiler which is opposite that of the combustion chamber the result of which is that the direct heat of combustion is near but never below the water at the bottom of the generator, and an extremely even distribution of heat to the generator is maintained. The natural tendency of the heat to travel upwardly from the grate is sufficiently counteracted to secure the desired results by this method of projecting the flame horizontally and of withdrawing the burnt products from the lower part of the space provided therefor.

In order successfully to use the vertical grate, instead of the horizontal grate, which has been heretofore used in connection with

steam generation for motor vehicles, it has been found necessary to counteract the tendency destructively to overheat the upper areas of the grate by the heat of the flame burning at the lower areas. This has been accomplished by the combined effect of projecting the flame and withdrawing burnt products as above described, constructing the grate with parts between the perforated areas projecting well into the mixing chamber, and of providing the grate with substantial marginal metal portions protected from the direct heat of combustion by heavy blocks of insulating material, so that the said cooler marginal or flange portions shall reduce, by conduction, the temperature of adjacent grate areas. In this way a surprisingly simple and effective method has been found to control the temperature of the grate proper without impairing the heat efficiency for steam generating purposes.

Another feature of the invention is the method and means for maintaining the vaporized fuel at high temperature up to the point of delivering into the mixing chamber. This is accomplished by enclosing the fuel pipe leading from the vaporizing tube and the nozzle connected therewith and delivering to the mixing chamber, within a substantially closed chamber communicating with the combustion chamber and positioned above the top thereof, so that said pipe and nozzle will be at all times maintained at approximately the temperature of the combustion chamber.

Another feature of the invention is the method and means for heating the air which is induced into the mixing chamber by the inductive action of the vaporized fuel. This is accomplished by providing an air chamber in close proximity with the combustion chamber and the chamber in communication therewith which partially surrounds said air chamber, and by positioning or controlling the intake to said air chamber, so as to protect the same from the cooling or other undesirable effects of the outside atmosphere.

Referring to the drawing, which illustrates, merely by way of example, suitable means for effecting the invention;—

Fig. 1 is a longitudinal vertical section on the line 1, 1 of Fig. 2.

Fig. 2 is a vertical cross-section on the line 2, 2 of Fig. 1.

Fig. 3 is a fragmentary horizontal section on the plane of line 3 of Figs. 1 and 2.

Similar numerals refer to similar parts throughout the several views.

In Fig. 1 is shown the steam generator or boiler having horizontal fire tubes, enclosed within walls forming, at one end of the boiler, the combustion chamber 11, having the vertical grate 12 forming one wall thereof, and, at the other end thereof, the space 11a for burnt products and the chimney exit 13 delivering from the lower part of said space. At the opposite ends of the horizontal fire tubes 14 are provided substantial spaces; in the space 11 to the right of the fire tubes (see Fig. 1) are positioned the fuel vaporizers 17 and 18, and also the steam superheater 19. In the space 11a to the left is positioned the feedwater heater 20. Above the fire tubes 14 of the generator or boiler 10 is the steam dome 21, and at the bottom is the settling space 22 provided with the blow-off pipe 23. The steam superheater 19 is connected to the engine by suitable piping not shown. The feedwater heater 20 is connected to a suitable water supply not shown. The normal water level in the steam dome is approximately on the broken line 24.

There are two vaporizers 17 and 18, in loop formation, each acting exactly in the same way. These vaporizers are connected to pipes 25 and 26 respectively, delivering from a source of fluid fuel under pressure, not shown.

These vaporizers deliver to the heads 27 and 28 respectively, which in turn deliver through branch pipes 29 to the discharge nozzles 30, which in turn deliver to the vertically arranged mixing tubes 31 within the mixing chambers 32. It will be noted that each of the vaporizers 17 and 18 forms two complete loops in front of the grate, and that the delivering end and its head lie directly in front of a pilot 34, so that the head forms a superheater for the vaporized fuel delivered to nozzles 30.

The mixing chamber 32 is separated from the combustion chamber 11 by the vertical grate 12. This mixing chamber, in the present example, is divided into four compartments, each provided with a mixing tube 31. The grate 12 is provided with two vertically extending channels 33, one in about the middle part of each half thereof. Within the channels 33 are positioned the pilots 34 extending downwardly from a point above the grate 12. These pilots are exactly alike, having perforated areas flush with the flanking perforated areas of the grate 12. These pilots are supplied with combustible mixture by means enclosed in housing 43,

separated from and unaffected by the heat of the main combustion chamber 11. The usual electric ignition devices, such as resistance wires 35 and 35', are associated with the pilots.

The vertical grate 12 is in corrugated form, that is, provided with vertically arranged perforated strips or areas 36 extending from top to bottom of the grate with interposed imperforate channeled strips 37 of V-shaped cross-section, as shown in Fig. 3. These integral imperforate V-shaped channeled strips 37 project well into the mixing chamber. They yield sufficiently to permit contraction and expansion of the grate as a whole to prevent breaking. They extend far enough into the mixing chamber to impart heat, by conduction from the adjacent perforated burner areas, to the combustible mixture. The incoming cooler air and fuel thus absorbs heat from the grate as a whole and thus contributes in maintaining the temperature of the grate within safe limits. The grate body 12 is also provided with substantial marginal flanges such as 38 and 38', for connection with the walls forming the combustion chamber 11, on the one side, and the mixing chamber 32 on the other side. The flanges 38 on the combustion side of the grate are protected by heavy blocks 39, of suitable heat insulating material.

It will be noted that the discharge ends or heads 27 and 28 of the vaporizers, the branch pipes 29 and the nozzles 30 are all enclosed in chambers 40, located above and in communication with the combustion chamber 11, that is, up to the extreme discharge end of the nozzles 30, so that the temperature of the vaporized fuel is maintained close to that of the combustion chamber, up to the point of discharge into the mixing tubes 31. It will also be noted that the vaporized fuel is discharged into the mixing tubes 31 through air chambers 41, from which the air to be mixed with the fuel is induced into the mixing tubes by the injected fuel. These chambers 41 are nearly surrounded by the chambers 40 and partake of the heat thereof, and the intakes to said chambers 41 may obviously be so located or controlled as to protect the chambers from the cooling effects, or atmospheric conditions, of the outside air.

In operation.—In starting the device the pilot is in the first instance provided with a combustible mixture comprising a liquid fuel which is vaporized and mixed with preheated air and the combustible mixture ignited by an electric heating resistance. The pilot causes the preliminary heating of the main vaporizer after which the fuel is turned into said main vaporizer from which it is delivered, mixed with air, into the main mixing chamber 32 from whence it issues through the multitude of grate burner vents and is ignited by the pilot. After the ignition of the combustible

mixture passing through the pilot grate 34, the current may be cut out of the heating resistance elements and the pilot may be kept burning.

5 The invention resides especially in the arrangement for steam generation, as above described, of the grate with respect to the mixing chamber and to the combustion chamber and the generator or boiler associated therewith; in the arrangement of the exit for burnt products, the means provided for protecting the grate from destructive overheating, and the means for maintaining the vaporized fuel and air at required temperature at the point 10 of entrance to the mixing chamber.

All of said features are combined to provide maximum constant heat from vaporized fuel for the even and constant generation of steam, without danger of injury to the generator by cause of excessive heat applied to parts thereof which are liable to become unprotected by water. The heat so applied to 20 said steam generation being derived from a combustion which is, to the greatest possible extent, unaffected by changes in atmospheric 25 conditions.

What I claim is:

1. In a device of the character described, the combination of a straight horizontal tubular boiler arranged to facilitate the flow 30 of heat therethrough uniformly distributed and in substantially horizontal lines of travel, a combustion chamber arranged at one end of said boiler, and a burner arranged on the 35 opposite side of said combustion chamber from said boiler, said burner comprising a mixing chamber for air and vaporized fuel and a substantially vertical grate forming the dividing wall between the mixing chamber 40 and the combustion chamber, said grate having a multitude of burner-vents corresponding approximately in area of distribution, with the group area of the boiler tube ends.

2. In a device of the character described, 45 the combination of a straight horizontal tubular boiler arranged to facilitate the flow of heat therethrough uniformly distributed and in substantially horizontal lines of travel, a combustion chamber arranged at one end 50 of said boiler, and a burner arranged on the opposite side of said combustion chamber from said boiler, said burner comprising a mixing chamber for air and vaporized fuel and a substantially vertical grate forming 55 the dividing wall between the mixing chamber and the combustion chamber, said grate having a multitude of burner-vents corresponding approximately in area of distribution, 60 with the group area of the boiler tube ends, and means forming an enclosed space for burnt products on the opposite side of the boiler from that of the combustion chamber provided with an exit for burnt products 65 near the lower part of said space.

3. In a device of the character described, the combination of a straight horizontal tubular boiler arranged to facilitate the flow of heat therethrough uniformly distributed and in substantially horizontal lines of travel, 70 a combustion chamber arranged at one end of said boiler, and a burner arranged on the opposite side of said combustion chamber from said boiler, said burner comprising a mixing chamber for air and vaporized fuel 75 and a substantially vertical grate forming the dividing wall between the mixing chamber and the combustion chamber, said grate having a multitude of burner-vents corresponding approximately, in area of distribution, 80 with the group area of the boiler tube ends, and means forming an enclosed space for burnt products on the opposite side of the boiler from that of the combustion chamber, a feedwater heater enclosed within said space 85 and an exit for burnt products positioned at the lower part of said space.

4. In a device of the character described, the combination of a straight horizontal tubular boiler arranged to facilitate the flow 90 of heat therethrough uniformly distributed and in substantially horizontal lines of travel, a combustion chamber arranged at one end of said boiler, and a burner arranged on the 95 opposite side of said combustion chamber from said boiler, said burner comprising a mixing chamber for air and vaporized fuel and a substantially vertical grate forming the dividing wall between the mixing chamber and the combustion chamber, said grate 100 having a multitude of burner-vents corresponding approximately in area of distribution, with the group area of the boiler tube ends, said mixing chamber having a plurality of compartments, each of which is provided with a mixing tube for delivering there- 105 to heated air and vaporized fuel.

5. In a device of the character described, the combination of a straight horizontal tubular boiler arranged to facilitate the flow 110 of heat therethrough uniformly distributed and in substantially horizontal lines of travel, a combustion chamber arranged at one end of said boiler, and a burner arranged on the opposite side of said combustion chamber 115 from said boiler, said burner comprising a mixing chamber for air and vaporized fuel and a substantially vertical grate forming the dividing wall between the mixing chamber and the combustion chamber, said grate provided with a multitude of burner vents arranged in areas separated by V-shaped imperforate channel formations projecting, 120 from the plane of the burner-vent areas, into the mixing chamber, the combined areas of said burner vents corresponding approximately with the group area of the boiler tube ends.

6. In a device of the character described, the combination of a straight horizontal tu- 125

- 5 bular boiler arranged to facilitate the flow of
heat therethrough uniformly distributed and
in substantially horizontal lines of travel, a
combustion chamber arranged at one end of
said boiler, and a burner arranged on the op-
posite side of said combustion chamber from
said boiler, said burner comprising a mixing
10 chamber for air and vaporized fuel and a sub-
stantially vertical grate forming the dividing
wall between the mixing chamber and the
combustion chamber, said grate having a
multitude of burner-vents corresponding ap-
proximately in area of distribution, with the
15 group area of the boiler tube ends and a con-
ductor for delivering vaporized fuel at high
temperature to said mixing chamber, so posi-
tioned an enclosed as to partake of the heat
of the combustion chamber up to the point of
said delivery.
- 20 7. In a device of the character described,
the combination of a straight horizontal tu-
bular boiler arranged to facilitate the flow of
heat therethrough, uniformly distributed and
in substantially horizontal lines of travel, a
25 combustion chamber arranged at one end of
said boiler, and a burner arranged on the op-
posite side of said combustion chamber from
said boiler, said burner comprising a mixing
chamber for air and vaporized fuel and a sub-
30 stantially vertical grate forming the dividing
wall between the mixing chamber and the
combustion chamber, said grate having a
multitude of burner-vents corresponding ap-
proximately, in area of distribution, with the
35 group area of the boiler tube ends, and means
for heating the air induced with the fuel com-
prising chambers and passages arranged so as
to partake of the heat of the combustion
chamber up to the point of said induction.
- 40 8. In a device of the character described,
the combination of a horizontal fire-tube boil-
er, a combustion chamber arranged at one end
of said boiler, and a burner arranged on the
opposite side of said combustion chamber
45 from said boiler, said burner comprising a
mixing chamber for air and vaporized fuel
and a substantially vertical grate forming the
dividing wall between the mixing chamber
and the combustion chamber, said grate hav-
50 ing a multitude of burner-vents correspond-
ing approximately, in area of distribution,
with the group area of the boiler tube ends.

PAUL R. DELLING.
